Primary Examiner — Mary Ann Calabrese*Assistant Examiner* — Catherine Ho(74) *Attorney, Agent, or Firm* — The Webb Law Firm(57) **CLAIM**

The ornamental design for a transport vehicle, as shown and described.

DESCRIPTION

FIG. 1 is a front view of a transport vehicle showing our new design;

FIG. 2 is a rear view thereof;

FIG. 3 is a left side view thereof;

FIG. 4 is a right side view thereof;

FIG. 5 is a top view thereof; and,

FIG. 6 is a perspective view thereof.

The broken line portion of the figure drawings is included to show portions of the article that form no part of the claimed design.

A bottom view is omitted because it is plain and unornamental and forms no part of the subject matter of the claimed design.
